UNITED STATES PATENT OFFICE.

WILLIAM HAIG RAMAGE, OF GIRARD, OHIO, ASSIGNOR TO VALLEY MOULD AND IRON CORPORATION, OF SHARPSVILLE, PENNSYLVANIA, A CORPORATION OF NEW YORK.

HOT TOP WITH INTEGRAL-BrICK LINING.

Application filed May 11, 1927. Serial No. 190,407.

The present invention relates broadly to metallurgy and more specially to hot tops for ingot molds.

Heretofore in the art, hot tops have been of two general types, one comprising a metal casing in which bricks are set to comprise the heat insulating material, and this type of hot top is adapted to have several pours of steel. The other type of hot top in general use comprises a hollow tile such as is used for large chimneys of residences, etc., and in this type the tile is unsupported and unprotected and is broken for each pour; that is, each ingot uses up one of these tile type of hot tops.

15 The present invention comprises the utilization of an integral one-piece hollow brick supported by a metal casing or frame in such manner as to permit the assembly to be securely fastened to an ingot mold and with 20 the integral brick so protected and supported by the casing that the hot top will withstand several pours before requiring a new brick.

While the drawings disclose a few preferred forms of the invention, it is realized 25 that the invention may be embodied in constructions other than those disclosed and therefore the disclosure is to be understood as illustrative and not in the limiting sense.

Fig. 1 illustrates a form of the invention in 30 section comprising an integral hollow brick within a metal casing and with the assembly locked upon an ingot mold.

Fig. 2 is a perspective view of the form shown in Fig. 1 with a portion of the casing 35 broken away to illustrate the cement locking rings.

Fig. 3 is a perspective view of another form of the invention comprising a skeleton metal shell supporting the hollow brick.

40 Fig. 4 is a sectional view of the hot top shown in Fig. 3 showing a fragment of the upper end of an ingot mold with the hot top in position.

Fig. 5 is a sectional view through a form 45 of the invention in which the integral brick extends into the ingot mold.

Fig. 6 is a sectional view of the invention 50 similar to that shown in Fig. 5 with the exception that the casing rests upon the top of the ingot mold.

Fig. 7 is a sectional view of a form of the invention comprising a supporting shell and a

removable base plate adapted to retain the integral hollow brick within the shell.

Referring to the drawings and more specifically to Figs. 1 and 2, the hot top comprises an integral hollow brick 1 which is made up and burned as an article of manufacture. Preferably, though not necessarily, this brick is provided with circumferential 55 grooves 2 which form recesses for supporting a binding material or cement. Preferably the opening 4 in the hollow brick 1 is inclined upwardly and inwardly in order to provide suitable draft so that an ingot may be stripped therefrom without binding or breaking the brick. Preferably the outside 60 of the brick is also inclined in the same direction. A metal casing 5 of cast iron or the like is provided with an internal opening adapted to cooperate with the external shape of the hollow brick so that when the casing is telescoped over the brick the two 65 form a sufficiently accurate bond to obviate placing any injurious or undue stress on any 70 localized part of the hollow brick, and with the casing coming to rest on the brick in such manner that the casing does not go down the full length of the brick so that the brick will not make an intermediate contact with the 75 upper end of the ingot mold 6. Preferably, though not necessarily, the casing 5 is likewise provided on its interior surface with circumferential grooves 7 which are so located as to be substantially opposite the 80

grooves 2 in the brick when the casing is in position on the brick. Prior to assembly of the brick and the casing the grooves 2 in the brick and the grooves 7 in the casing are filled with suitable cement and a very thin 85 layer of cement may also be laid over the exterior surface of the brick. When the casing is telescoped over the brick the fresh cement in the grooves in the casing unites with the fresh cement in the grooves in the 90 brick so that when the cement is hardened, circumferential keys of hardened cement fill these adjacent grooves and securely lock the 95 brick within the casing.

In Figs. 3 and 4 the form of the invention 100 comprises an integral hollow brick 10 which is supported and surrounded by a skeleton shell. This shell 11 preferably comprises cut-out sheet metal shaped to fit the

exterior of the integral brick. The shell may comprise two identical parts 12 and 14, each of which are provided with top flanges 15 and with side flanges 16 which are adapted 5 to be held together by bolts 17. In this form the bolts may be so tightened that cement may not be necessary to hold the frame and brick together. However, where there is a 10 tendency of the frame to become loosened this tendency may be overcome by utilizing cement to hold the frame in place on the brick.

Fig. 5 illustrates a form of the invention 15 similar to Fig. 1 with the exception that the hollow integral brick 20 is provided with a shoulder 21 adapted to sit on the top of the ingot mold 22 and the brick has an extension 24 which extends a slight distance into the mouth of the ingot mold. The casing 25 20 and the cement keys 26 illustrated in Fig. 5 are substantially the same as shown in Figs. 1 and 2.

In Fig. 6 the construction illustrated 25 comprises a hollow brick 30 which extends into the ingot mold 31 and which is supported and protected by a cast metal casing 32 that is provided with a bottom flange 34 adapted to sit upon and form a metal to metal joint with the flat surface 35 on the top of the ingot 30 mold 31. This hollow brick may likewise be held within the casing by cement keys 36.

Fig. 7 illustrates an integral hollow brick 40 which fits within an integral casing 41 that is provided with lugs 42 adjacent the lower 35 edge thereof. A removable flange 44 bears against the lower end of the hollow brick 40 and may be secured to the casing 41 by means of bolts 45 passing through the flange and cooperating with the lugs 42. In this construction the flange 44 is adapted to form a tight metal to metal joint with the top surface 46 of the ingot mold 47.

In Figs. 1 and 2 the hot top is shown as being held in position on the ingot mold by 45 means of the stirrup members 50 which pass under the lugs 51 on the ingot mold 6 and are attached to the ears 52 on the side of the casing 5 by means of key-bolts 54. While in this particular view a specific form of attaching means is illustrated, it is to be understood that each of these hot tops is adapted 50 to be attached by some such means to the ingot molds with which they are intended to cooperate whenever it is desired to permanently secure the hot tops in place during use.

The foregoing types of hot tops, each of which comprises a single hollow burned brick and a metal supporting casing, are more permanent in their characteristics than the lined 60 casing hot tops of the known art for the reason that heretofore where supporting casings or shells have been used either individual separate bricks have been set in the shells or cement has been plastered within the shell to 65 build up a cement lining. Where bricks in

sections are set in the shell there is a liability of steel fins forming in the joints between the bricks and thereby breaking the bricks when the ingots are stripped and the fins are withdrawn. Where cement is set in the shells it is not possible to dry this cement to the extent of a burned brick and therefore when the molten steel strikes the cement it tends to cause the same to loosen and disintegrate. In the present invention, with the integral 75 burned brick, there are no joints for the formation of fins and full advantage is taken of being able to burn the hollow brick outside of the shell and then securely setting the same in the shell, thereby providing a substantially permanent structure adapted to withstand many pours or heats before requiring replacement.

Having thus described my invention, I 80 claim:

1. A hot top for ingot molds comprising a hollow burned brick comprising an integral member, a metal supporting shell surrounding said brick and adapted to circumferentially compress said brick, said shell extending substantially the full height of said brick, and means to anchor said shell to an ingot 90 mold.

2. A hot top for ingot molds comprising a hollow burned integral brick, a supporting 95 and metal shell enclosing said hollow brick, and being adapted to apply compression forces circumferentially around said brick, means to attach said shell to an ingot mold, and means to interlock said brick and said 100 shell.

3. A hot top for ingot molds comprising a hollow burned integral brick, a supporting and metal shell enclosing said hollow brick, and being adapted to apply compression 105 forces circumferentially around said brick, and means to interlock said brick and said shell, said shell terminating above the bottom edge of said brick to permit said brick to sit on the top of an ingot mold and overhang the 110 matrix of the mold.

4. A hot top for ingot molds comprising an integral burned hollow brick, the exterior of said brick comprising upwardly and inwardly inclined side walls, a metallic shell 115 having the inner side wall surfaces adapted to form intimate contact with the exterior surfaces of said brick when said shell is telescoped over said brick, the exterior surface of said brick being provided with a recess and the exterior surface of said shell also being provided with a recess, and locking means within the recess in the shell and also the recess in the brick to lock said brick within said shell.

5. A hot top for ingot molds comprising an integral burned hollow brick, the exterior of said brick comprising upwardly and inwardly inclined side walls, a metallic shell having 120 the inner side wall surfaces adapted to form

intimate contact with the exterior surfaces of said brick when said shell is telescoped over said brick, the exterior surface of said brick being provided with a recess and the exterior surface of said shell also being provided with a recess, said brick having side walls of substantially uniform thickness, locking means within the recess in the shell and also the recess in the brick to lock said brick within said shell, and securing means to firmly attach said hot top to an ingot mold.

6. A hot top for ingot molds comprising an integral hollow burned brick having upwardly and inwardly inclined exterior surfaces provided with a circumferential groove, a metal supporting shell adapted to fit the ex-

terior of said brick and also provided with a circumferential groove adapted to be positioned substantially opposite the groove in the brick when the brick and shell are in telescoped relation, and suitable cementing means within said grooves adapted to lock said brick within said shell.

7. A hot top for ingot molds comprising a hollow integral brick lining with the inner wall inclined upwardly and inwardly, a metallic casing supporting the outer wall of said lining, locking means to secure the hot top to the mold, and means to retain said lining within the casing when the hot top is stripped from an ingot.

WILLIAM HAIG RAMAGE.
